UNITED STATES PATENT OFFICE.

JOHN P. MURPHY, OF PORTLAND, AND NAPOLEON W. RANCOURT, OF LEWISTON, MAINE.

LEWIS-BOLT.

No 821,952.

Specification of Letters Patent.

Patented May 29, 1906.

Application filed May 24, 1905. Serial No. 262,020.

To all whom it may concern:

Be it known that we, JOHN P. MURPHY, a resident of Portland, and NAPOLEON W. RANCOURT, a resident of Lewiston, State of Maine, citizens of the United States of America, have invented certain new and useful Improvements in Lewis-Bolts, of which the following is a specification.

Our invention relates to a lewis-bolt of the ordinary type in which two inverted-wedge-shaped sections are used with a key inserted between them adapted to hold them apart. Such bolts are used in holes made larger at the bottom than at the top to prevent the withdrawal of the bolt. As these bolts are now made the parts are all separated, and in placing them in position and connecting on the shackle much time and much trouble are required.

The object of our invention is to construct such a lewis-bolt so that the parts will be held together in such a position that they are always ready to be inserted and quickly adjusted.

We illustrate our invention by means of the accompanying drawings, in which—

Figure 1 is a front elevation, and Fig. 2 is a section, on the line $x x$ of Fig. 1.

a are the two inverted-wedge-shaped members, having eyes at their upper ends, through which pass the pin b . This pin is provided with a central opening, through which passes the wedge-shaped key d for separating the sections a . Means are pro-

vided for holding the key in position, and for this purpose we form in it a longitudinal slot d' , extending a portion of the way through the key and terminating back from the ends, so that the slot is closed at its ends.

The inner end of the screw e , which passes through the pin b , enters the slot and holds the key from dropping out when not in use.

The upper end of the key d is of course wider than the lower end, and when a wider spread is desired in the members a the key is drawn up and reversed, the pin b revolving in the eyes. The shackle c is secured on the outer ends of the pin b and completes the device, which forms a self-contained lewis-bolt always ready for use and easily and quickly adjusted for either wide or narrow holes.

We claim—

1. The herein-described lewis-bolt consisting of a pair of inverted-wedge-shaped members each having an eye at the upper end, a pin passing through said eyes, said pin having a central opening therethrough, a wedge-shaped key passing through said opening and having a longitudinal slot therein, terminating back from the ends of the key and a screw in said pin adapted to enter said slot to hold said key in place.

2. The herein-described lewis-bolt consisting of a pair of inverted-wedge-shaped members each having an eye at its upper end, a pin passing through said eyes, said pin having a central opening therethrough, a wedge-shaped key passing through said opening and having a longitudinal slot therein, terminating back from the ends of the key, a screw in said pin adapted to enter said slot to hold said key in place and a shackle secured by said pin.
